PUMP

Frank C. Woelfer, Jr., Cincinnati, Ohio, assignor
to The Cincinnati Ball Crank Company, Cincinnati, Ohio, a corporation of Ohio

Application March 9, 1940, Serial No. 323,195

8 Claims.

(Cl. 103—5)

This invention relates to pumping apparatus primarily used for pumping grease or the like from a drum and delivering the same to a point of use under pressure. More particularly, the invention is directed to pumping apparatus of that type adapted to be mounted on the top of a grease container and including a tube depending into the container to a point adjacent the bottom thereof. The invention relates as well to a pumping mechanism including an improved pneumatic motor. These so called "barrel" pumps have been designed to lift the grease from the drum to a high pressure pump contained in the same unit which delivers the grease under high pressure for supplying the fittings of a motor car.

It has been an object of the present inventor to provide an improved pumping mechanism for lifting the grease from the bottom of a container to a high pressure unit and from this point delivering the grease under high pressure to the point of use. The improved mechanism, although driven by the same power unit will not stall due to oversupply of grease to the high pressure pump. It will be appreciated that it is impossible to deliver a fixed amount of grease upon each normal stroke of the lifting or low pressure pump, and that in time the high pressure pump will be oversupplied or undersupplied. If undersupplied, the pump is inefficient and wasteful and if oversupplied, the operativeness of the mechanism is seriously affected for it will stall. Realizing that the output of the lift pump cannot be uniform, the present inventor has provided means for creating a slight reserve supply of grease in the chamber adjacent the high pressure pump and at the same time means for preventing too much accumulation. Since the space in which the low pressure pump is mounted is limited, the present inventor has provided that this last named means may also function as the intake means for the low pressure pump. In the disclosed embodiment means employed for this purpose is constituted by a valve which has a double function either opening for intake purposes for the low pressure pump or opening for bypassing purposes in the event of an oversupply of grease to the high pressure pump.

It has been a further object of the inventor to provide an extremely compact assembly or relationship of the low pressure pump, the high pressure pump and, the power means which drives the pistons of these pumps as a unit.

It has been a further object of the inventor

to provide an improved air motor for supplying the power for operating the pumps.

It has been a further object to provide an improved means for mounting the pump mechanism relative to the original container whereby the pump may be quickly and easily placed in position where its low pressure pump is submerged in the grease in the original container. The mechanism including the valved piston device is disclosed and claimed in a co-pending divisional application Serial No. 442,923, filed May 14, 1942, entitled Pumps, which application was divided from this application.

Other objects and certain advantages will be 15 more fully apparent from a description of the drawings in which:

Figure 1 is a perspective view of a pumping mechanism incorporated in a cabinet with its lower pressure pump submerged in the grease in 20 an original container.

Figure 2 is a perspective view showing the pumping unit mounted on the top of a shorter type of grease bucket and illustrating a cooperating base arrangement.

Figure 3 is a sectional view taken vertically 25 through the center of the apparatus showing the details thereof, with the pumping mechanism in position to start upward in the grease delivery stroke.

Figure 4 is a fragmentary sectional view of the lower end of the tube containing the low pressure pump showing the pump piston descending with the valve thereof in intake or open position.

Figure 5 is a view taken similar to Figure 4 30 showing the low pressure pump piston moving upwardly in the delivery stroke.

Figure 6 is a sectional view taken on line 6—6 of Figure 3, showing more of the details of the air motor.

Figure 7 is a sectional view taken on line 7—7, 35 Figure 6, illustrating the valve mechanism for the air motor in position for causing the air motor piston to move upwardly in the grease delivery stroke.

Figure 8 is a view taken similar to Figure 7 but fragmentary thereof showing the valve tripped for exhausting the lower chamber of the air motor for causing the loading stroke.

Figure 9 is a fragmentary view showing the 40 external face appearance of the valve unit.

Figure 10 is a diagrammatic view showing the air motor moving in the upstroke or grease delivery stroke.

Figure 11 is a diagrammatic view taken similar to Figure 10, showing the air motor moving

in the downward stroke with the air below it being exhausted through the valve.

Referring now to Figure 1 of the drawings, the pump assembly is shown in working position above a grease drum 1 which is housed in a cabinet 2. The cabinet includes a hinged door at its side and a base which is provided with wheels to facilitate movement of the unit. An air intake conduit 3 supplies air under pressure to the pump assembly while a high pressure grease hose 4, leading from the pump to a grease discharge nozzle 5, provides a controlled means for dispensing the grease. A pair of brackets 6, fixed to the wall of the cabinet 2, support the pump assembly so that its intake, which is a cylinder 7, depends from the head of the pump into the grease drum.

In Figure 2, the pump assembly is shown as a modified form in which it is being utilized to pump from a small bucket-type grease container. In this instance a housing 8 is provided for the head of the pump. A plurality of springs 9 cooperate with a ring cover 10, fixed to the pump head, above the grease bucket and a ring base 10a below the bucket to hold the assembly firmly in place. In this instance, the intake cylinder 7 is shortened.

Generally speaking, the pump assembly comprises an air motor 11, a low pressure large volume pump 12, and a high pressure small volume pump 13. The low pressure pump 12 is disposed below the air motor and sucks grease from the drum and delivers it through a bypass to the high pressure plunger above the air motor. The air motor and pump plungers are in alignment and interconnected so that they reciprocate together.

The low pressure pump 12 operates in the intake cylinder 7. The upper end of cylinder 7 is threaded as at 15 to be secured to and depend from the air pump casing, shown generally at 16, which houses the air motor 11. The lower end of cylinder 7 is internally threaded to receive an intake cap 17. An aperture 18 in the bottom of the cap 17 provides an intake opening. A bridge 19, spanning the aperture 18, spaces the intake cap from the bottom of the grease drum so that the aperture 18 cannot become closed.

At its upper or inner side, the aperture 18 provides a seat for a check valve 20. Valve 20 is generally disc-shaped having its under, peripheral edge beveled to insure a proper seal when seated. A plurality of guiding fingers 21 extend outwardly and upwardly from the upper face of the check valve 20 parallel to and in slidable contact with the inner face of the intake cap so that the valve remains centered with respect to the port 18. A set screw 22, extending through the wall of the cap 17, limits the upward movement of the check valve.

The pump 12 is connected to the air motor through a connecting rod 23 (Figure 3). The piston 24 of the pump 12 is slidably supported on the rod 23 between two coil springs. A counterturned section 27 of the rod 23 provides a shoulder 28 which is engaged by the upper end of the spring 25. The lower end of the spring 25 is engaged by the top of the piston 24.

The piston 24 comprises a head 29 which is slidably engaged around the counterturned section 27 of the rod 23. The head is similar to an inverted thimble in that an internal counterbore provides a chamber 30. A plurality of discharge passages 31 is bored through the head to open the chamber 30 to the upper side of the piston.

The wall of chamber 30 is threaded at 32 to receive a tubular nipple 33 which has a radial flange 34 extending outwardly from its outer wall just below its threaded section. The flange 34 cooperates with the downwardly extended rim 35 of the inverted thimble-like head 29 to hold in place a cup piston ring 36. The bottom flange of the cup piston ring is clamped between the rim 35 and the flange 34 when the nipple 33 is screwed tightly into the chamber 30.

A sleeve 38 is engaged over the rod 23 inside the chamber 30. Its outside diameter is smaller than the inside diameter of the tubular nipple 33, so that a passage 39 exists between the two. The sleeve 38 rests upon the head of a valve retainer sleeve 41. When the piston is at rest, as shown in Figure 3, the sleeve 38 has its upper end spaced slightly from the top of the chamber 30. The valve retainer sleeve 41 is engaged around a counterturned portion 42 of the rod 23 and its head abuts the shoulder which is provided by the counterturned portion.

A valve 43 is urged upwardly against the collar by the action of the spring 26 disposed around the bushing 41 under compression between the valve and a washer 44 which is held in place by a nut 45 threaded on the end of the rod 23. The nut also holds the bushing 41 tightly against the shoulder of the piston rod. The downwardly extended rim or edge of the tubular nipple 33 constitutes a seat which is engaged by the spring urged valve 43.

The head of the pump assembly comprises: a cylinder block 46 which has a bypassage 47 and a cylinder bore 48 in which a piston 49 of the air motor 11 reciprocates; a casing 50 which includes the high pressure pump 13; and a head 51 which constitutes a guide for the piston 49.

The connecting rod 23 extends upwardly from the pump 12 coaxially with the cylinder 7, and enters the air motor cylinder 48 through a packing gland 52. The upper end of the rod 23 is threaded into a nut 53 which in turn is threaded into the lower face of the piston 49 of the air motor. The nut 53 has a radial flange 55 which engages a double cup gasket 56 and secures it between the flange 55 and the lower face of the piston 49. A metal ring 57 is interposed between the radial flanges of the two cups to stiffen the gasket 56.

A counterturned shoulder 57 in the upper end of the cylinder 48 seats a cup packing gland 59. The head 51 includes a flange 60 at its lower end which is bolted to the flange 58 of the cylinder block and holds the packing gland in place. The packing gland 59 provides a seal around the piston 49. The gasket 56 and packing gland 59 provide two chambers in the cylinder bore.

One pressure chamber 62, below the gasket 56, has an effective area equal to that of the cylinder bore minus the cross section of the rod 23. The other pressure chamber 63, above the piston, has an effective area equal to that of the cylinder bore minus the area of the piston.

The chamber 62, below the piston 49, has an inlet and exhaust which is controlled by a valve means (disclosed at a later point in the specification), while chamber 63, above the piston ring, is under constant air pressure.

The downstroke of the piston 49 results due to the fact that the pressure is relieved below the piston and the normal head of pressure above the piston forces it down. Although the air pressures are the same on both sides, the upstroke or power movement occurs due to the larger

area of contact on the bottom of the piston. Moreover, the air acting on this larger area produces the high pressure. The downstroke is a low pressure loading stroke.

The head 51 mounted on the top of the cylinder block, has an internal bore 65 into which the piston of the air motor extends when it is moved upwardly on its power stroke. The lower end of the casing 50 for the high pressure cylinder 67 depends into the internal bore 65. The piston 49 is tubular as at 68 except for its lower end so as to clear the casing.

The upper portion of casing 50 is fitted into a central bore 70 in the top of the head 51. A counterturned portion of bore 70 provides a shoulder 72 which abuts a shoulder 73 on the casing to secure it against upward displacement. The upper end of the casing is threaded internally as at 74 to engage threads on the lower end of the grease supply head 71. A hexagonal flange 75, just above the threads on the head 71, engages the top of the head 51 so that as the head 71 is threaded into the housing the shoulder 73 on the housing is drawn up against the shoulder 72 in the bore 70, thus fixing the casing 50 in place.

The outer wall of the cylinder 67, near its upper end, has a counterturned section which provides a shoulder 77. The cylinder is held in place by the nuts 78 of a packing gland 79, at its lower end which nut is threaded into the casing 50. When the nut 78 is tightened, the shoulder 77 on cylinder 67 is forced against a shoulder 80, which is on the inside of the bore in the casing 50.

The high pressure plunger 13 extends axially from the center of the piston 49 and upwardly through the packing gland 79 into the bore of cylinder 67. The plunger is held in place by a head at its lower end which is engaged between the nut 53 and the piston 49.

A counterbored section 81 in the upper end of the bore of the casing 50 contains a valve member 82. A ball check valve 83 is loosely mounted in the lower portion of the valve member and closes against a seat 84 when moved upwardly. The ball is retained by a pin 85 which passes horizontally through the member 82 below the valve. The upper portion of the valve member is tubular and extends partially up into the bore of the grease supply head 71. A shoulder 87 on the valve member engages the lower edge of the head 71 and is forced downwardly against a shoulder 89 provided by the counterbore 81. A plurality of intake ports 90 are provided around the mid-section of the valve member. The counterbore 81 is larger than the valve member so that a chamber 91 is provided around the intake ports 90. The grease delivery to the high pressure piston is through a pipe 92 from the bypass chamber 47 in the cylinder block. Pipe 92 is threaded into the casing 50 in a line with the plurality of intake ports 90. A port 93 in the casing 50 between the pipe 92 and the ports 90, connects the two.

As stated above, inlet and exhaust valve means are provided as a control for the air pressure in the cylinder bore beneath the piston 49. The valve means is actuated by a yoke 95 which extends outwardly from a ring 96 which is bolted to the top of the piston 49. The yoke extends through a slot 97 in the wall of the head 51 and engages a groove 98 at the upper end of a vertically slidable rod 99. Therefore, the rod 99 (Figures 6 and 7) reciprocates with the piston 49,

sliding in a vertical bore in the cylinder block 46.

The midsection of the rod 99 is accessible from the outside of the cylinder block through an opening 101. The bifurcated end 102 of a toggle 103 extends into the opening 101 to engage a counterturned section 104 of the rod 99. The counterturned section is of substantially greater length than the swing of the toggle 103 to provide a certain amount of clearance. The toggle is actuated at the end of each stroke of the piston 49.

A valve support 105 is bolted to the cylinder block 46. A gasket 107 is interposed between the valve support and the cylinder block. An opening 106 is provided in the base 105 to correspond to the opening 101. The toggle 103 is supported by a pin 108 which is set in a pair of ears 109 extending outwardly from the base 105, one on either side of the opening 106. The toggle 103 consists of two upright arms joined at their bases. Above and centered, with respect to the pivot point provided by pin 108, another pin 112 provides a rocking support for a collar 113 on the lower end of a pin 114. The pin 114 extends upwardly through the middle of a contact wedge 115. The wedge is urged upwardly against a pair of fingers 117 by a spring 116. The fingers extend from the base 105 on both sides of the pin 114. This arrangement provides a snap action toggle.

The outer end 118 of the toggle 103 is bifurcated and straddles a counterturned section 119 of a valve plunger 120. Section 119 is only slightly less in length than the complete swing of the toggles 103, so that the shoulders at the ends of the section 119 are hit sharply by the outer end of the toggle 103, when it rocks.

As shown in Figure 7, the valve plunger 120 passes downwardly through a central bore 121 in an exhaust head 122. The exhaust head is provided with a plurality of exhaust ports 123 which open a central chamber 124 in the head to the atmosphere. The head is threaded into the top of the valve chamber which extends from the base of the valve support 105.

A ledge 125 in a bore 126 inside of the valve chamber provides a valve seat 127. A valve 128 is constituted by a flange at the upper end of a sleeve 129 engaged around a counterturned section of the plunger 120 in the bore 126. The inner end of the head 122 includes a rim which constitutes another seat 130 for the valve opposite to the seat 127. The movement of the valve is preferably only about $\frac{1}{16}$ of an inch so that the change over from one seat to another takes a minimum of time. The lower face of the valve 128 is beveled to close more tightly on the seat 127. The upper face of the valve 128 supports a packing ring to provide a seal when the valve is closed against the seat 130.

The sleeve 129, which has the valve 128 at its upper end, is fixed to the plunger 120 between a shoulder 131, provided at its upper end by the counterturned section, and a cup piston ring assembly 132 which is held in place by a washer 133 and a nut 134. The nut is threaded on the lower end of the plunger 120.

The air intake conduit 3 which supplies the air pressure to the motor is connected at two points to the motor. One line 135 extends into the cylinder of the air motor above the cup gasket 56 and is always open. The other line 136 enters the bore 126 below the valve seat 127 and is alternately closed from and opened into a port 137 extending to the cylinder of the air motor below the cup gasket ring 56.

Referring to the diagrammatic view, Figure 10, when the plunger 120 is up at the end of the downward movement of the air motor piston, the air comes in through the line 136 past the valve seat 127 and through the port 137 to the chamber 62 below cup piston ring 56. As the piston 49 is moved upwardly, the air above the gasket is forced back through the bore 135 into the conduit 3. When the plunger 120 is down (Figure 11), the air supply to chamber 62 is closed at the valve seat 127 and chamber 62 is opened to the atmosphere past the seat 130. Allowing the air pressure in the chamber 63, above the cup piston ring 56 to effect the return of the piston 49.

When the piston of the air motor moves upwardly, the low pressure grease pump 12 forces grease up through the cylinder 1 through the bypass and port 93 and through the ports 90 into the head. At the same time, the high pressure plunger is moving upwardly, and since the grease above it in the bore of the cylinder 67 is under greater pressure than the grease in the head, the ball check valve 83 remains closed. The grease under high pressure is forced from the bore of cylinder 67 into a bore 139 in the casing wall which is below the check valve and above the upper extremity of the plunger's stroke. A nipple 140, threaded into the bore 139 through the wall of head 51 comprises the outlet for the grease.

On the down stroke of the piston, the check valve 83 opens and grease is forced by the air above it in the head and by suction, past the valve 93 into the high pressure cylinder bore. At this time, the low pressure pump moves downwardly, opening as it moves (Figure 4), to allow grease to pass through it.

The nipple 140 extends from the head 51 and is engaged by a T 142 at its outer end. A bleeder valve assembly 143 is threaded into the end of the T 142 opposite the nipple 140. The bleeder valve comprises a tube 144 having a valve seat which seats a valve 145 fixed on a stem 146. The section of plunger outwardly from the valve 145 is square and has threads at its four corners for engagement with internal threads in the tube at this point. A pin 147 is fixed in the outer end of stem 146 to facilitate turning. When the collar 145 is unseated by unscrewing the stem, a passage is opened past the flat sides of the square end of the stem. This is provided so that any air that is in the system when the unit is set up can be released easily at this point.

The inner end of the stem beyond the valve 145 is cone shaped to fit into a concavity in the square base 148 of a seat for a spring 149. The coil spring 149 extends to the other side of the T 142 and urges a ball check valve against a seat 150 in the inner end of the nipple 140. The other arm 151 of the T 142 is counterbored to provide a seat 152 which seats a ball check 153. Ball check valve 153 is urged against its seat by a spring 154. The other end of spring 154 is engaged by the inner end of a threaded section 155 of a swivel coupling 156. Beyond the coupling 156 an elbow fitting 158 has the high pressure grease hose 4 connected to it.

This pump is fastened or disposed with respect to the original container in a number of ways. In Figure 3, a plate 160 is provided providing a flange 161 around its outer edge adapted to overhang the flange of the opening in the top of a drum of lubricant or adapted to overhang the edge of the drum. This cover plate carries lugs 162 providing inclined bores in which hooks 163 are slidably mounted. The hook portions are

disposed around the flange within clearances 164 and are adapted to engage the side of the flange of the drum opening or the edge of the drum. The shanks of the hook bolts extend through the bores of the lugs and wing nuts 165 are screwed thereon bearing against the lugs for drawing the hooks into position. A sleeve 166 is disposed coaxially with the pump and includes a horizontal flange 167 bolted to the cover. The sleeve fits about the circular lower end of the air pump casing 168.

In Figure 1 the pump unit is mounted on a ledge 169 within the cabinet 2 and depends into the drum generally shown at 170. In Figure 2, the base 10a serves as a support for the short type grease bucket 171. The springs 8 are disposed under tension between hooks on the base and cooperating hooking means 172 disposed on the cover plate 10 fixed to the casing or the housing 8 of the pump.

Description of operation

In operating the pump, it is mounted in any one of the ways shown so as to disclose its tube or cylinder 1 in the grease drum. The pump intake 18 of the low pressure pump, is then disposed adjacent the bottom of the drum. The nozzle 5 of the grease discharge hose is extended to the point of use. Air is admitted through the air intake conduit 3 and enters the pressure chambers 62—63 in the pump cylinder. This assumes that the valve for the air motor 11 is in the position shown in Figure 10. The air is at the same pressure in both of the chambers. It forces the pump piston 49 upwardly due to the difference between the area of piston exposed in the lower chamber 62 and that exposed in the upper chamber 63. Therefore, the air in chamber 63 is never lost.

When the piston 49 reaches the end of its upstroke, the valve is tripped through its mechanism and the lower chamber 62 is then open to the atmosphere as shown in Figure 11. As the air motor piston moves up, the piston of the low pressure pump 12, is drawn up in the tube 1 and grease is lifted to the chamber 11 above the high pressure cylinder 67. As the air motor piston moves up, it also moves the piston of the high pressure pump 13. The high pressure piston causes the valve 83 to close in the high pressure cylinder and the grease is forced out through the line 4 past the check valves therein. In other words, as the grease is being lifted under low pressure for supply purposes for the high pressure pump, the high pressure pump is delivering a high pressure charge through the conduit 4.

In the event that there is too much grease in the tube and the pressure above the high pressure cylinder becomes too great, the resistance to the upstroke of the piston will unseat the valve 43. This occurs when the pressure in the grease is greater than the force of the spring 26 which holds the valve 43 in seated position. The result is then that the grease by-passes through the piston and the rest of the stroke is lost motion. The suction valve 20 at the base of the cylinder 1 will open to admit the grease as the piston is moving up.

Now as the air motor moves down, the valve 20 closes (see Figure 4) and the descending rod 23 carrying the low pressure piston slides through the low pressure piston assembly unseating the valve against the pressure of the spring 26. Thus the grease is free to flow through the piston into

the tube above it. As the high pressure piston descends, the vacuum created by the retraction of the high pressure piston draws a supply of grease into the high pressure cylinder. The head 71 is constantly filled with grease and this accumulated supply column of grease is always available just over the high pressure cylinder. Each time the high pressure piston delivers a charge of grease under high pressure, the low pressure system lifts a supply.

It is impossible to provide a constant supply on each stroke and the volume of grease in the supply chamber varies. In this arrangement, a safety arrangement is provided. Excessive amounts are by-passed and stalling (such as would occur if the grease becomes too tightly packed in the supply chamber) is prevented. The same valve which permits filling of the tube above the piston brings about this by-passage of oversupply.

The chamber provided in the head 71 over the high pressure cylinder provides a space in which the grease may accumulate. This chamber is referred to as an accumulating or charging chamber since it is just above the high pressure chamber. The moment the high pressure piston starts down, the grease moves into the high pressure cylinder, not only because of expansive pressure in the grease but because of the suction created by the movement of the high pressure piston. Thus it is provided that the high pressure cylinder is immediately completely filled with grease and the discharge stroke is entirely effective.

It will be noted that there is very little agitation of the grease. This, of course, is advantageous since "churning" or undue working of the grease back and forth in the pump tends to break through the body of the grease. As the low pressure piston moves down through the grease, the grease flows through it. As it moves up, the grease is elevated. If there is too much grease above the piston, the valve unseats and the grease is by-passed back below the piston. It will be noted that the grease which is by-passed, that is the grease directly below the piston, is picked up on the next stroke so that no specific quantity of grease is agitated over and over again.

Having described my invention, I claim:

1. In a lubricant pumping mechanism, an air motor, a tube extending from said air motor adapted to be submerged in the grease within a grease drum, said tube constituting a low pressure cylinder and including an inlet, a high pressure cylinder disposed above the air motor, a piston in the low pressure cylinder, a piston in the high pressure cylinder, said pistons attached axially to the piston of the air motor, a grease supply conduit extending from the low pressure cylinder, by-passing the cylinder of the air motor and communicating with the high pressure cylinder, and a discharge conduit extending from said high pressure cylinder.

2. In a pumping unit, a low pressure pump, a high pressure pump disposed above the low pressure pump, a conduit extending from the low pressure pump to the high pressure pump, means operating said pistons of said pumps unitarily in lubricant feeding and discharge strokes whereby the low pressure pump supplies the high pressure pump while the high pressure pump discharges the grease, and means in said conduit for maintaining a constant supply of lubricant under pressure for charging said high pressure pump.

3. In a lubricant pumping mechanism, a power

5 piston and its cylinder, a tube disposed below said cylinder and adapted to be submerged in the grease within a lubricant drum, said tube constituting a low pressure cylinder, a high pressure cylinder disposed above the power cylinder,

10 a piston in the low pressure cylinder, a piston in the high pressure cylinder, said pistons attached axially to the power piston, a lubricant supply conduit connecting the high pressure cylinder and the low pressure cylinder, a discharge conduit extending from said high pressure cylinder, and a charging chamber disposed over the high pressure cylinder for containing a supply of lubricant adapted to be drawn into said high pressure cylinder.

15 4. In a pumping unit, a low pressure pump, a power source, said low pressure pump depending from said power source, a high pressure pump disposed above the power source, and a conduit extending from the low pressure pump to the high pressure pump, the pistons of said pumps fastened unitarily to said power source and adapted to operate in lubricant feed strokes in the same direction whereby the low pressure pump supplies the high pressure pump while the high pressure pump discharges the grease supplied in the preceding low pressure strokes.

20 5. A lubricating pump comprising, a high pressure cylinder and piston, a low pressure cylinder and piston, said pistons coaxially disposed, common means for reciprocating said pistons said low pressure cylinder disposed downwardly and consisting of an elongated tube having an inlet valve at the base thereof, a charging chamber 30 adjacent and connected to the high pressure cylinder, and a grease flow conduit between the low pressure cylinder and said chamber.

25 6. A lubricating pump having a power means and comprising a high pressure cylinder and piston, a low pressure cylinder and piston, said pistons coaxially disposed, said low pressure cylinder disposed downwardly and consisting of an elongated tube having an inlet valve at the base thereof, a grease flow conduit between the low pressure cylinder and said high pressure cylinder, a charging chamber formed in the grease flow conduit adjacent to and in communication with the high pressure cylinder, and means for bypassing an excess supply of grease from said low pressure pump.

35 7. In a pump, a high pressure cylinder, a high pressure piston in said cylinder, an accumulator chamber disposed adjacent to said high pressure cylinder, conduit means for supplying grease to said accumulator chamber, means for maintaining said chamber filled with grease at all times, said chamber providing an enlarged area adjacent to the intake to the high pressure cylinder for containing a supply of grease adequate for each filling stroke of the piston and, a valve controlling the intake of grease to the high pressure cylinder.

40 8. In a lubricating pump, a high pressure cylinder and piston, a low pressure cylinder and piston, an air motor cylinder and piston, said pistons disposed coaxially and attached together, a valve operating ring attached to said air motor piston above the cylinder and extending laterally beyond the cylinder, and a toggle valve for controlling the air supply to the air motor cylinder, said toggle valve actuated by the extension of said ring, said valve fixed to the outer wall of the cylinder.

FRANK C. WOELFER, JR.
